INVENTOR
A. GIRTANNER

BY A. GRITANNER
E. E. Huffman
ATTORNEY

UNITED STATES PATENT OFFICE.

ALEXANDER GIRTANNER, OF NEW YORK, N. Y.

ASH CONVEYER.

Application filed July 6, 1920. Serial No. 394,213.

To all whom it may concern:

Be it known that I, ALEXANDER GIRTANNER, a citizen of the United States of America, residing at the city of New York, State 5 of New York, United States of America, have invented a certain new and useful Ash Conveyer, of which the following is such a full, clear, and exact description as will enable any one skilled in the art to which it appertains to make and use the same, reference being had to the accompanying drawings, forming part of this specification.

My invention relates to an ash conveyer and more particularly to the manner 15 of lining an elbow section of such conveyer.

In the accompanying drawings which show as much of one form of ash conveyer as is necessary to illustrate my invention, Figure 1 is a vertical section, Figure 2 is an 20 end view, Figure 3 is a side elevation of the elbow, and Figure 4 is a top plan view of the elbow, a portion of the horizontal arm being broken away.

5 indicates the elbow section of an ash 25 conveyer which section is provided with a vertical arm 6 and a horizontal arm 7 to which are secured, by bolts or otherwise, a vertical pipe section 8 and a horizontal pipe section 9 respectively. The horizontal pipe 30 section 9 and horizontal arm 7 of the elbow may be provided with a removable lining 10 as shown in Figure 1 of the drawings. This lining, however, forms no part of the present invention.

The vertical arm 6 of the elbow 5 is provided with a removable lining consisting of a pair of front and rear parts 11 which are exactly alike in form so as to be reversible, and a second pair of side parts 12 which are 40 also alike and reversible. By making the parts 11 and 12 reversible the life of the lining is prolonged by changing the parts when one shows greater wear than the other.

The parts 11 and 12 terminate somewhat 45 below the upper face of the arm 6 and the pipe section 8 is provided with a lining 13 projecting into the arm 6 and abutting with the parts 11 and 12. In this way a good joint is secured between the parts 6 and 8.

50 14 is a removable end plate which is held in

position by means of bolts 15 and in turn secures in position an impact plate 16 preferably formed of two or more parts as the greatest wear comes on this part of the device and by forming the impact plate 16 of a 55 number of parts several wearing surfaces are secured. The upper edge of the impact plate 16 abuts the front part 11 and thus hold the same in position. 17 is a removable bottom plate held in position by bolts 18. This plate 60 17 has its upper face arranged somewhat below the upper face of the lining 10 so as to form a sump for collecting the water of condensation from the steam jet injected into the device by means of a nozzle 19 carried by 65 the said bottom plate 17. The bottom plate 17 is also provided with a discharge outlet 20 for discharging the water of condensation from the sump. This passage 20 is provided with a valve 21 which normally rests upon a 70 lever 22 provided with a rod 23 for manually operating it. When steam is admitted thru the nozzle 19, the rod 23 is operated to bring the valve into closed position, after which it is held in position by the suction 75 formed in the conveyer until the steam is shut off, when it will automatically drop open to allow the water of condensation to be discharged from the sump.

In order to secure a tight joint between 80 the various sections of the conveyer, I provide each of the contacting surfaces with a V-shaped groove 24 in which grooves are placed cylindrical strips 25 of a compressible metal or alloy, preferably lead. This strip 85 25 is made somewhat larger in diameter than the side of the channel formed by the two meeting grooves so that when the parts are drawn together the metal will be pressed out to more or less completely fill the channel 90 and thus form an air tight joint between the parts.

I claim:

1. An elbow section for ash conveyers, the upwardly extending arm of which is provided with a removable lining consisting of two pairs of parts, the parts of each pair being interchangeable.

2. In an elbow section for ash conveyers, the combination with an upwardly extending 100

arm, of a removable lining in said arm consisting of two pairs of parts, the parts of one pair being wedge shaped and the parts of each pair being interchangeable.

5 3. In an ash conveyer, the combination with an elbow section, the upwardly extending arm of which is provided with a removable lining situated within the elbow section

and consisting of two pairs of reversible parts, a pipe section connected to said upwardly extending arm, and a lining in said pipe section and extending into the elbow and abutting said removable lining.

In testimony whereof, I have hereunto set my hand and affixed my seal.

ALEXANDER GIRTANNER. [L.S.]
